(57) **CLAIM**

The ornamental design for a storage package for information media, as shown and described.

DESCRIPTION

FIG. 1 is a top plan view of a first embodiment of a storage package for information media showing our new design, in an open orientation;

FIG. 2 is a side elevational view thereof, the view from the opposite side being a mirror image thereof;

FIG. 3 is an end elevational view thereof, taken in the direction of the arrow 3 of FIG. 2;

FIG. 4 is an end elevational view thereof, taken in the direction of the arrow 4 of FIG. 2;

FIG. 5 is a bottom plan view thereof;

FIG. 6 is a side elevational view thereof in a closed orientation and to an enlarged scale, the view from the opposite side being a mirror image thereof;

FIG. 7 is a front end elevational view thereof, taken in the direction of arrow 7 of FIG. 6;

FIG. 8 is a rear end elevational view thereof, taken in the direction of arrow 8 of FIG. 6;

FIG. 9 is a sectional view thereof, taken along the line 9—9 of FIG. 7;

FIG. 10 is a top plan view thereof; and,

FIG. 11 is a sectional view thereof, taken along the line 11—11 of FIG. 10.

The stippling in the drawing indicates non-transparent appearance—for example, due to frosting, coloring or the like.
